United States Patent Office.

FREDERICK KILIAN, OF NEW YORK, N. Y.

Letters Patent No. 101,628, dated April 5, 1870.

IMPROVED FOLDING CHAIR.

The Schedule referred to in these Letters Patent and making part of the same.

To all whom it may concern.

Be it known that I, FREDERICK KILIAN, of the city, county, and State of New York, have invented a new and useful Improvement in Folding Chairs; and I do hereby declare the following to be a full, clear, and exact description thereof, which will enable those skilled in the art to make and use the same, reference being had to the accompanying drawing forming part of this specification, in which drawing—

Figure 1 is a sectional side elevation, which shows the chair ready for use.

Figure 2 shows it folded together.

Similar letters indicate corresponding parts.

This invention relates to folding chairs, and consists in a peculiar construction and arrangement of parts whereby simplicity and economy of construction are obtained; and the bottom and back of the chair are made capable of two different positions or inclinations when set up for use, and, when folded together, to be set aside or for transportation, it is still supported upright on its feet.

The letter A designates the back of the chair. It extends in one piece from the floor to the extreme height of the chair, and its lower ends form the front feet, and its upper end is made with a curve, whose concavity is toward the front of the chair.

That part of the back which is above the level of the seat is wholly or partly upholstered, as shown at B.

The letter C designates the part which forms the hind feet.

The parts A and C are pivoted to each other at D, at a point nearly at the center of the part C.

The part A, as well as the part C, are not each a single piece of wood or iron, but are made of several pieces composing a frame, which are united by rods E at the bottom, and are otherwise suitably connected together.

To the upper end of the part C I pivot the forward ends of the side bars F of the seat G.

The said side bars F have longitudinal slots, H, extending nearly from end to end of the bars, and which slots receive pins I, that project from the sides of the back A of the chair into the slots, so as to connect the seat or its bars to the back.

In fig. 1 the pins I are represented as being at the

bottoms of the slots H, where the pins are arrested, and the further outward movement of the parts A C is prevented, the seat G being thereby secured, so that the chair is ready to be occupied.

The slots H in the side bars or sides of the seat G enable me to vary the angle at which the seat and the back are arranged with regard to each other, as I will next explain.

This variation I accomplish by forming notches, J, along the edges of the slots H, which notches are intended to receive the pins I, and hold the back A and the seat G at various positions, so as to make them more nearly straight or more inclining, as desired.

Only one side or end of the chair is shown in the drawing, but the opposite side is made in the same manner, and with the same parts and slots as the side that appears in the view.

When it is desired to fold the chair, the tops of the part A C are simply drawn toward each other until the back A and the outer part of the seat G touch each other, when the feet of said parts A and C will remain apart far enough to form a support for the chair in its folded state, so that it can continue to stand upright. This result I accomplish by curving the part C inward from the pivot D to its top, so that, when the top of the part or leg C comes against the back, the legs will remain asunder a sufficient distance to make the chair, in its folded state, self-supporting.

The top of the seat G is upholstered, and the pivot, which connects it to the leg C, is the rod which holds the front of the seat-frame together.

What I claim as new, and desire to secure by Letters Patent, is—

The combination and arrangement together in a folding chair of the parts A C G and pins I, the side bars or sides of the seat G being slotted, as shown, and provided with adjusting notches J, and the upper part of the leg C being curved inward, substantially as and for the purpose described.

This specification signed by me this 20th day of January, 1870.

FR. KILIAN.
